United States Patent

Des. 234,640
Patented Mar. 25, 1975

234,640

STERILIZER

Frank A. Zagara, Pittsford, N.Y., assignor to
Sybron Corporation, Rochester, N.Y.

Filed Dec. 7, 1972, Ser. No. 313,184

Term of patent 14 years

Int. Cl. D23—04; D24—01
U.S. Cl. D83—1 W

FIG. 1

FIG. 2

FIG. 3

FIG. 4

FIG. 5

FIG. 1 is a front elevation of a sterilizer showing my new design;

FIG. 2 is a rear elevation thereof;

FIG. 3 is a side elevation thereof;

FIG. 4 is a top plan view thereof; and

FIG. 5 is a side elevation as seen from the opposite side of FIG. 3.

I claim:

The ornamental design for a sterilizer, substantially as shown and described.
